ABSTRACT

A printer carriage is operated to space a document by using a counter which may be set by program command to any count from a single increment which is a submultiple of a line space to a maximum count of the total number of increments for a full page. The counter is operated to subtract in response to each step advance by the carriage motor until a predetermined count is reached at which a stopping sequence is initiated to stop the carriage at the desired number of increments.

FIG. 6b

MULTIPLE PITCH CARRIAGE LINE SPACING

CROSS-REFERENCE TO RELATED APPLICATIONS

This invention is related to the inventions of copending applications Ser. No. 661,929 of Frederick W. Schaaf filed Aug. 21, 1967 (now U.S. Pat. No. 3,499,516) and Ser. No. 661,930 of Roger C. Hull and Eugene T. Kozol filed Aug. 21, 1967 (now U.S. Pat. No. 3,508,637), and is shown applied to the carriage control circuits of said applications.

FIELD OF INVENTION

This invention relates to printer carriage control systems, and it has reference in particular to multiple pitch line spacing in printer carriage control systems.

DESCRIPTION OF PRIOR ART

Heretofore change of line pitch in high-speed printers has been accomplished by stopping the printer and changing ears, or has been limited to a dual mode such as by changing from six to eight lines per inch by means of a latch which is used to preset a counter to one of two counts in order to reach a fixed maximum count after the desired number of steps, as in the above-referenced copending application Ser. No. 661,929 of Frederick W. Schaaf filed on Aug. 21, 1967 (now U.S. Pat. No. 3,499,516) and assigned to the assignee of the present invention.

SUMMARY OF INVENTION

Generally stated, it is an object of the invention to provide a new and novel line pitch control system for printers.

More specifically, it is an object of this invention to provide a multiple line pitch control system for a high-speed printer.

Another object of the invention is to provide a line pitch control system for a printer which is operable either as a dual pitch system under stored program control or which can operate in response to specific commands at any of a wide range of line pitch values.

Yet another object of the present invention is to provide for operating the carriage in a printer by using a stepper motor in which each step increment is but a fraction of the distance required for one line advance.

Still another object of the invention is to provide a flexible multiline pitch control system which is compatible with current programming and is also capable of operating in accordance with specific increment commands over a wide range of line pitch values.

In a preferred embodiment of the invention, advance of a document in a printer is effected by a carriage in which a carriage motor advances the document by increments, several of which are required for a one-line advance. Control of the motor is effected by a counter which has a capacity equal to the product of the number of steps per line multiplied by the number of lines per document.

When operating in one mode, the counter is advanced in accordance with a stored channel command in a carriage control buffer which is scanned position by position and a count of one is subtracted in response to each motor advance pulse until a predetermined minimum count is reached at which the speed of the motor is reduced preparatory to stopping.

In another mode, the counter is advanced by specified increments in accordance with commands from a central processing unit to space the document any number of increments up to the maximum and a count of one is subtracted for each motor advance pulse until the counter reaches a predetermined minimum count, whereupon the speed of the motor is reduced prior to stopping.

The foregoing and other objects, features and advantages of the invention will be apparent from the following more particular description of a preferred embodiment of the invention as illustrated in the accompanying drawing.

DESCRIPTION OF THE DRAWING

In the drawing:

FIG. 1 is a partial schematic showing of one type of printer apparatus with which the invention may be used;

FIGS. 2a through 2t taken together provide a schematic circuit diagram of a tapeless carriage control system which may be used with the carriage of FIG. 1 and embodies the invention in one of its forms;

FIG. 2u is a block diagram showing the relationship between the principal elements of FIGS. 2a-2t;

FIG. 3 is a block diagram showing the arrangement of FIGS. 2a through 2t;

FIG. 4 is a chart showing typical carriage control codes used in the control system of FIGS. 2a-2t;

FIG. 5 is a chart showing typical codes to define line positions other than the last line of a form;

FIGS. 6a through 6b are charts showing valid commands for control of a printer carriage utilizing the invention; and

FIG. 7 is a clock timing chart.

DESCRIPTION OF A PREFERRED EMBODIMENT

FIG. 1 shows a printer apparatus of one type with which the present invention may be used; and comprises a type carrier 10 having a plurality of individual type elements 11 movable in a continuous path on a stationary frame 12. A portion of the path of motion of the type elements 11 includes a straight portion along which printing can occur and which hereinafter is referred to as the print line. Each type element 11 has one or more different engraved characters on the surface thereof adjacent the print line. Plural sequences of type characters are obtained by assembling the type elements 11 in predetermined arrangements on the frame 12. The type elements 11 are driven preferably in the form of a train along the frame 12 so that they travel at a constant velocity and are maintained in abutting relation along the straight portion of the path of travel.

The printer apparatus of FIG. 1 is a back printer which is described in U.S. Pat. No. 3,241,480, which issued on Mar. 22, 1966 to James M. Cunningham, and in accordance with well-known operational principles thereof a paper document 13 is positioned behind an ink ribbon 14 or the like which in turn is positioned immediately adjacent the type elements 11 over the print line portion thereof. The ribbon 14 may be fed in a suitable manner between spools 15 and 16 along the line of travel of the type elements 11. The paper document 13, however, is fed transversely to the direction of motion of the type elements 11. Guide bars 17 and 18 and carriage forms feed tractors 19 coact to support and move the paper document 13 in the proper line of travel. Generally, printing occurs while the paper 13 is stationary relative to the print line. On completion of a print cycle, the paper 13 is advanced one or more spaces by the carriage tractors 19 to a position where a new line of data may be printed. The means for feeding the paper 13 in synchronism with operation of the print mechanism are well known in the art and may include a carriage drive motor 22 comprising, for example, dual motor units 22-1 and 22-2 or the like connected to shafts 20 by means of pulleys 21 or the like of the carriage tractors 19.

In the printer apparatus of FIG. 1, the arrangement shown is for a back printer. This arrangement is merely used by way of example and not by way of limitation, since the invention may be as readily used with a front printer. As shown, printing occurs when the paper 13 and ribbon 14 are impacted against the type characters on the type elements 11. The impacting occurs at various print positions along the print line to eventually form a complete line of data. For this purpose, a plurality of print hammers 24 are mounted behind the print medium 13. Print hammers 24 are arranged to be uniformly spaced so that one hammer 24 occupies each print position along the print line, and the hammers 24 are aligned in a single row parallel to the print line. Each print hammer 24 is a part of an individual hammer unit which comprises an electromagnet 26 with an armature 28 and a push rod connector element 30 with a bias spring 32 which maintains the hammer 24 out of contact with the paper 13 when the electromagnet 26 is

deenergized. Each hammer 24 is individually operable and the operation of the various hammers 24 occurs selectively at random positions along the print line in accordance with instructions from control means which comprises a type tracking device and a coating storage device which indicates the particular data to be printed. Further details of a suitable control system may be more fully understood by reference to U.S. Pat. No. 2,993,437 of F. M. Demer and E. J. Grenchus for a High Speed Printer, which issued July 25, 1961.

Heretofore, control of the tractor drive motor 22 for advancing the paper 13 to the different line positions at which printing is desired had been controlled by means such as described in U.S. Pat. No. 2,531,885 to A. W. Mills et al., which issued on Nov. 28, 1950, and is entitled "Paper Feeding Device."

As therein described, control of the document feed was obtained by using a paper tape having a plurality of channels in which holes were punched at the particular line positions to which a skip operation was to be effected. A plurality of brushes aligned with these channels sensed the holes punched therein, and under the control of channel selecting commands from a processing unit, effected stopping of the document at the desired line positions.

The copending application of Frederick W. Schaaf, application Ser. No. 661,929, filed Aug. 21, 1967 provides for replacing the punched paper tape control system and its sensing brushes with a carriage control buffer 40 wherein are stored binary coded representations of the channels containing the different skip commands, these representations being stored at the respective line positions to which a skip operation is to be effected.

The Carriage Control Buffer 40 in the present instance is substantially identical with that in the Schaaf application and comprises a 16×16 core array containing 256 bytes, with core planes for an end of document Flag bit, 1, 2, 4, and 8 bits and a parity bit P. As shown in FIGS. 2g and 2h, the buffer 40 is provided with a plurality of X drivers 42 and corresponding X switches 44 for providing drive current in the X direction. Y drivers 46 and Y switches 48 provide the corresponding Y drive. Inhibit drivers 50 and AND-gates 51 are provided for selectively controlling the writing of information into the buffer 40 in response to data on the Carriage Control Buffer data bus 52. Sense amplifiers 54 gated by a Voltage Sense Level circuit VSL which establishes a minimum threshold level of signal to obtain an output from the Sense Amplifiers 54, and AND's 55 provide for readout of the buffer 40, Flag, 1, 2, 4, 8 and P bit lines of the several core planes.

Addressing of the buffer 40 is effected, as described in the Schaaf application, by means of a CCB Address Register 56 shown in FIGS. 2d and 2e, and which comprises a plurality of triggers 56-1, 56-2, 56-4 through 56-128 arranged in a binary addressing fashion for addressing of the buffer 40. Triggers 56-1 and 56-2 are decoded by AND's 43a-43d to form unique output lines for controlling the X drivers 42, while triggers 56-4 and 56-8 are similarly decoded by AND's 45a-45d to control the X switches 44. Likewise, triggers 56-16 and 56-32 address the Y drivers 46 through AND's 43e-43h, while triggers 56-64 and 56-128 address the Y switches 48 through AND's 45e-45h. The address register 56 is advanced by pulses from a clock 60 shown in FIGS. 2i and 2j, and which comprises a plurality of triggers 60-1 through 60-4 and decode AND's 61a-61k with associated inverters 63a-d, single shots 63e-f, and drivers 63g-i. Drive of the clock triggers 6-1 through 60-4 is obtained from a clock run trigger 62 through AND 64 in conjunction with pulses from an oscillator 36. The trigger 62 is set through AND 68 and OR 70 by an adapter start signal from OR 84 through AND 82, in response to a write command from OR 38c (FIG. 2n) during loading of the buffer 40, and by a carriage clock start signal from AND 180 (FIG. 2f) during readout of the buffer 40.

In order to avoid inadvertent modification of the carriage control buffer 40 contents, loading of the buffer 40 is effected in the same manner as in the Schaaf application, in response to

a CCB load command which follows a specific channel tag line sequence which is sensed and stored in a gate load latch 72a shown in FIG. 2b, and which must be set before the CCB load latch 72c can be set. An UCB load latch 72b also shown, controls loading of a universal character buffer (not shown). These latches 72a-c respond to commands on the bus out lines 69 through decode AND's 74a-74c, respectively. AND 59 and OR 47 (FIG. 2p) provide an invalid CCB address 1 signal at AND 59. Require NOT signals are obtained from the bus out lines 69 through inverters 71a-k and decode AND's 73a-f (FIG. 2a) OR 71m provides a bus out 6 or 7 signal. Control of the CCB address register 56 during loading is effected by a buffer control latch 80, shown in FIG. 2f, which is set by the CCB load signal through OR 81 or by the output of AND 79. Data from the channel is loaded under the control of the I/O tag lines service-in and service-out which gate signals from OR 38c and one of OR's 39a-c through AND 82 and OR 84 (FIG. 2n) which provides an adapter clock start signal for setting the clock trigger 62 (FIG. 2i). OR 39d provides an input to OR 84, while OR 39a also provides inputs to OR's 38a-c. Data is gated to a CCB register 83 (FIG. 2k) comprising a plurality of latches 83a-f for comparison through OR's 76a-h and AND's 77a-c with command signals in a command register 78, (FIG. 2e), comprising latches 78a-e which are controlled from the Bus Out 69 through OR's 85a-f and decode AND's 86a-k from the system Bus Out 69 with the following byte relations.

Bus Bit	CCB Register Bit
4	8
5	4
6	2
7	1
3	F

The data is gated to the register 83 by means of a plurality of AND's 87a through 87l and OR's 88a-f to the latches 83a-f, and to the CCB data bus 52 for controlling the inhibit drivers 50 for storing data bits in the several planes of the different positions in the buffer 40 of FIG. 2h. AND's 87m and 87n provide gating signals to different ones of the AND's 87a-l for manual and normal operations, respectively. Exclusive OR's 89a-e provide a parity bit for the latch 83a. Reset of latches 83a-f is provided through AND 90.

Readout of the CCB Buffer 40 in connection with carriage operations may occur with or without printing. When printing, operation of the carriage tractors 19 to advance the document 13 the necessary amount is effected by energizing a dual carriage motor 22-1, 22-2 of FIG. 1, which may comprise stepper motors of a well-known type, in response to energization of carriage drive pulse circuit 96 comprising stepping triggers 96A and 96B as shown in FIG. 2t and as described in more detail in the copending application Ser. No. 661,930 of Roger C. Hull and Eugene T. Kozol, filed Aug. 21, 1967, now U.S. Pat. No. 3,508,637. These triggers 96A, 96B are sequentially stepped in increments each of which, for example, advances the document 13 one forty-eighth of an inch which is but a small fraction of a single line space in response to a Stepper Motor Advance signal through OR 100, in response to an Initial Advance signal from a single shot 102, or pulses from a plurality of emitter pickup heads 104, and 106 associated with a slotted emitter disc 111 driven by motor 22-1, 22-2 through amplifiers 108b-c, single shots 109a-b, 107, and AND's 110e-g (FIG. 2s). The outputs from the emitter heads 104, 106 are gated by means of outputs signals from a Low Speed latch 120, a Medium Speed latch 122, and/or a High Speed latch 124 (FIG. 2t) for operating the Carriage drive motor 22 at low, medium and high speeds. Selective control of these Low, Medium and High Speed latches 120, 122 and 124 is effected in accordance with the present invention through OR 119 (FIG. 2r), and AND's 121i-n in conjunction with OR's 122a and 122b, OR 125 and Downshift and Upshift latches 126a-b which inhibit the Medium and High Speed latch outputs momentarily when shifting from one to another speed, by an Increment Counter 150 (FIG. 2r) which deter-

mines how far the document 13 is to be advanced, whether one increment or more. The High Speed emitter signal is produced from the Medium Speed emitter head 106 by inversion through inverter 105 to drive single shot 107.

The Increment Counter 150 comprises a plurality of binary stages 1-1024 arranged to ripple add and ripple subtract, and with provision for DC entry for direct setting so it can be selectively set to a programmed increment value in response to increment data on Bus Out lines 69 through AND's 154a-k in conjunction with an Increment Command from the Bus Out 69 through AND 116, (FIG. 2q), Latch 75e(FIG. 2r), and AND 147 which also provides an Increment Carriage Go signal through inverter 149 and single shot 182.

The Increment Counter 150 is also arranged to be ripple advanced when operating in single, double or triple space modes, or in accordance with stored channel images in the carriage control buffer 40 by clock pulses from clock 60 in increments of eight for six lines per inch pitch and six for eight lines per inch pitch through AND's 195a-c.

The Increment Counter 150 is reversible and ripple subtracts or decrements one increment for each Motor Advance pulse from OR 100.

The output of the Increment Counter 150 is decoded through suitable decode circuits 197 to provide Increment counts of 1, 2, 3, 4-7, > 8, > 32, > 24, > 84, 72 and >3, which are used in the AND's 121a-n and OR 119 for selectively controlling the Low, Medium and High Speed latches 120, 122, 124, the Upshift and Downshift latches 126a-b and a plurality of Stop Generators 133-135 having adjustably timed stop pulses, in conjunction with Stop latches 182a-e and AND's 205a-e.

Stop generators 133, 134 and 135 are shown in FIG. 2s as comprising respectively a single shot 133a, for a single stop pulse; three single shots 134a-c with single shot 134a connected in parallel cascade with a sandwich of single shots 134b, c and an inverter 134d through an OR 134e for two stop pulses; and individual stop generators 135A-F each comprising a series parallel arrangement of single shots 135a-f and inverters 135g-i through OR 135j for three stop pulses as shown for stop generator 135A. The stop pulses are applied to the drive circuit 96 through OR 223 and OR 100 (FIG. 2t). By using single shots 135a-c-e in the several stop generators 135A-F of generators 135, having adjustable time intervals in a range of 1-3 ms., for example, different rates for the three stop pulses may be provided for each of different ones of the stop generators 135A-F to provide smooth stopping for the different increment values.

A Carriage Compare latch 159 (FIG. 2f) is provided for producing a reset signal at Single Shot 161 for the Carriage Register 56 during skip operations as will be explained hereinafter. Reset of latch 159 is provided at RO time through AND 117a. In order to provide for controlling single-space, double-space and triple-space operations, a space counter 214 is provided, (FIG. 2e), comprising a pair of triggers 214a, 214b which are driven by clock pulse R3, Not Carriage Register Skip, and Buffer Control through AND 216 to count clock cycles. AND's 218a-c compare the count of the clock cycles with the command in the Command Register 78 (FIG. 21) at time WO to produce through OR 219 an artificial Compare signal to reset the Carriage Start Latch 140 (FIG. 2f) after one, two or three clock cycles respectively, during which the carriage advances as many increments as are necessary for one, two or three lines. Triggers 214a, 214b are reset by Carriage Register Reset Signal from Single Slot 161 which also resets the Increment Counter 150.

Operation of the clock 60 during readout with a printing operation is effected under the control of a Carriage Control Buffer Address Counter gate trigger 136 (FIG. 2f) which is set by a Carriage Start Latch 140, through AND 192 and OR 194. Operation of the carriage drive circuit 96 (FIG. 2t) is effected by means of the Carriage Start Latch 140 (FIG. 2f) which is turned on either by an Immediate Carriage Go signal from single shot 138 and AND 139 (FIG. 2q) or by a Carriage Go

After Print signal from AND 148, if a print operation is involved. These signals set the latch 140 through OR 144 from AND 142 or from AND 148 and AND 146, respectively. Set of the Start latch 140 provides in addition to turning CCB Add Counter Gate Trigger 136 on, a Carriage Go pulse through AND 141 for setting the Low Speed latch 120 (FIG. 2t) through OR 119 (FIG. 2r) and a carriage not go pulse at inverter 141a, the increment counter 150 being advanced at times R3 and W1 by clock pulses through AND's 195a-b or c a count of six or eight for each clock cycle, depending on whether the line pitch is eight or six lines per inch, to start carriage operation. Stopping of the carriage is effected by resetting the Low Speed latch 120 through operation of the Increment Counter 150 (FIG. 2r) through AND 121m and providing a fixed number of stop signals through stop generators 133, 134 and 135 depending on the count of the Increment Counter 150. Stop latches 182a-e (FIG. 2s) are set by increment counts of 4-8 to control associated stop generators 135B-F. The Low Speed latch 120 is reset by a signal generated at an Increment count of 3 in AND 121m in response to a Not Motor Advance signal at single shot 101 from inverter 99 (FIG. 2t).

Status latches 164a-d (FIG. 2p) provide Busy, Channel End, Device End Gate, and Device End signals, indicative of the operating condition of the apparatus, through decode AND's 165a-g, associated OR's 166a-g, and AND's 92 and 185. Single shots 165h and 164e provide timed Print Ready and Not Device End Sample signals, respectively. Sense latches 176a-e (FIG. 2q) provide indications of the equipment error conditions to the system bus.

Tag line signals represented by the Service-In and Status-In signals are produced by tag line latches 168a, 168b (FIG. 2o) 35 for control purposes, through decode AND's 169a-g and OR's 170a-e. Bus assembly circuits are provided in FIGS. 2m-n, including decode AND's 157a-f, AND's 158a-q, OR's 167a-e and line drivers 155a-i for assembling the Bus In bits. Parity bit for the Bus In is provided by Exclusive OR's 178a-g, inverter 179 and AND 181. Bus Out parity check is provided by Exclusive OR's 189a-h through line receivers 156a-i.

DESCRIPTION OF OPERATION

45 In operation, the Carriage Control Buffer 40 (FIG. 2h) is loaded in response to a CCB Load command through decode AND 74c (FIG. 2b) from over the Bus Out lines 69, which sets the CCB Load latch 72c, provided that the CCB Gate Load latch 72a has been previously set by a command through decode AND 74a (FIG. 2b). The CCB Load latch 72c initializes the operation by resetting the CCB Address Register 56 (FIGS. 2d-e) to address 1 through OR's 171, 172, single shot 173, and OR 174, and sets the Buffer Control latch 80 through OR 81 (FIG. 2f). The Buffer Control signal gates the triggers 56-1 and 56-2 of the CCB Address Register 56 at each RO time to permit sequencing of the CCB addresses in each clock cycle. OR 174 also provides a delayed reset pulse from inverter 174a and single shot 174b to the CCB address register 56.

60 Since the command to load the buffer 40 has been stored in latch 72c, and the buffer address has been modified to the correct starting point, buffer byte 1, the control system is prepared to receive the data from the channel. The data is loaded under the control of the I/O tag lines Service-In and Service-Out through AND 82, (FIG. 2h), which produces the Adapter Clock Start signal at OR 84. This sets the Clock Run trigger 62 (FIG. 2i) through OR 70 and AND 68, starting the clock 60 and permitting it to take one cycle. The Clock Run trigger 62 resets at the fall of trigger 60-4 of the clock 60, which corresponds to RO time as shown in FIG. 7. Since the clock cycle is 2 microseconds, which is less than the minimum data period for a byte of data received from the Bus Out lines 69, the clock 60 will return to RO time before the next data byte is available.

A CCB parity bit is generated from the CCB register contents and is inserted in the bit latch 83a of the register 83 on an odd parity basis through the exclusive OR's 89a-d of parity circuit 89 (FIGS. 2k-l). The k-y drivers and switches 42, 46 and 44, 48 (FIG. 2g) are turned on to read by a Read signal at R1, R2, and R3 time as shown by the timing chart in FIG. 7. However, the contents of bit 1 in the Carriage Control Buffer 40 are not recycled because in loading the Buffer 40 a Strobe signal (which is a delayed signal produced by a time generator 38 in response to a Read signal) rises only on a read operation does not occur on loading, and output of the Sense Amplifiers 54 (FIG. 2h) did not, therefore, rise, so that the old contents of the Carriage Control Buffer 40 are erased during loading.

As described previously, data is loaded starting from position 1, and reset of the CCB Address Register 56 occurs with the coincidence of RO time and the CCB flag bit indicating the end of the form to be printed from AND 175 through OR 174 (FIGS. 2d-e). The clock 60 continues through the end of the current cycle and at RO time the CCB Address Register 56 will be advanced to position 2. The contents of position 1 remain in the CCB register 83. Should a program error occur during loading, as evidenced by the 0, 1, or 2 bits on Bus Out 69, a program error is indicated by an Invalid CCB Load signal generated by latch 176b, through OR 173a, AND 177c, or AND 177b and OR 173b (FIG. 2g). Other sense latches 176a, 176c, 176d and 176e function with AND 177a and OR 173c to provide a Command Reject signal; OR 173d and AND 177b to provide an Invalid Flag signal; and OR 173e to provide a CCB parity check and a Carriage Failure Check. AND 177d provides another input to latch 176b through OR 173a, AND 177c and OR 173b.

Carriage operations may occur with or without printing. The carriage commands shown in FIGS. 6a and 6b reflect this by describing the byte structure for an operation with a print command or for a carriage command alone. If the function is to Space/Skip Immediate, the Carriage Control latch 75a (FIG. 2c) is set through AND 53b, OR 65b, and decode AND 66a. Reset is effected through OR 75e. If a Write and Space/Skip command is sensed, the Write latch 75b will be set through OR 51a, and OR 51b, AND 53a, OR 65a and decode AND 66b. Reset is through OR 75f. In either case, a carriage function is indicated so that Gate Carriage Register signal rises at OR 77 (FIG. 2c) to permit loading of the bus-out bits from Bus Out 69 to the Carriage Command register 78 (FIG. 21) through AND's 86a, c-e-g and i. Decode AND's 66c and 66d provide control of CCB Read latch 75c and sense latch 75d, respectively.

To perform a carriage function, the Carriage Start latch 140 (FIG. 2f) is set through OR 144 either by the Carriage Go After Print signal from AND 146 and AND 148, or the Immediate Carriage Go signal from AND 142 through single shot 138 and AND 139 (FIG. 2g) when a carriage command bit configuration exists from Bus Out 69 and the Command-Out tag line rises. If the carriage or tractor 19 is not already in motion, Carriage Start latch 140 starts it by bringing up Carriage Go at AND 141 (FIG. 2f). The carriage or tractor 19 will be started in the low-speed mode by the Carriage Go signal setting the Low Speed latch 120 (FIG. 2f) through OR 119 (FIG. 2r).

Assuming a carriage command is entered into the Command Register 78 (FIG. 2f) gated by a Gate Command Register signal from AND 65b, (one of a group of ANDs 65A-54C (FIG. 2b) providing signal inputs to different ones of the Command Latches 75a-75d (FIG. 2c) to space one line, then the Skip latch 78e of the Carriage Command register 78 will be off. The Not 2 bit of the Single Space command is applied to AND 218a (FIG. 2e) for forcing a compare with the counter 214 when the clock advances the space counter 214 to a count of one. Carriage motion starts as follows: The Carriage Go signal from AND 141 (FIG. 2f) sets the Low speed latch 120 (FIG. 2f) giving the carriage an Initial Advance pulse from single shot 102 (FIG. 2s) and starting motion by advancing the motor drive triggers 96A and 96B (FIG. 2f)

which switch current to drive the motor 22 (FIG. 1) in a well-known manner. Additional advance pulses occur from the motor emitters shown in the Schaaf U.S. Pat. No. 3,499,516 through OR 100 so that the Increment Counter 150 (FIG. 2r) will be decremented for a preset increment count by the Stepper Motor Advance signal, and its contents are decoded by the decode circuits 197. For a pitch of six lines per inch, eight pulses total are required for a single space advance, and for eight lines per inch, six pulses are required.

- 10 The CCB Address Counter Gate trigger 136 (FIG. 2f) is set by the on output of the Carriage Start latch 140, in response to Immediate Carriage operation at AND 142, causing set of the Buffer Control latch 80 through AND 79 and OR 81, and starting the clock 60 by raising Carriage Clock Start at AND 180 and applying a signal to Clock Run trigger 62 through OR 70 and AND 68 (FIG. 2i). Reset of CCB Address Counter Gate trigger 136 is effected at W1 time, being gated in AND 136a by Buffer Control and the CCB Address Counter Gate trigger 136 ON output. AND 136b insures the proper timing relative to settling of the carriage 19. The OFF output of CCB Address Counter Gate trigger 136 gates reset of Buffer Control latch 80 at RO time in AND 196. The clock 60 takes one cycle stopping in RO time. In doing so, the contents of the CCB byte 2 are read out to the CCB register 83 and the CCB Address Register 56 (FIG. 2d-e) advances to position 3 at RO time. The Increment Counter 150 was advanced by clock pulses R3 and W1 or W1 through ANDs 195a-c, to count 6 or 8 depending on whether the pitch was eight or six lines per inch.
- 15 30 Space Counter 214 (FIG. 2e) through OR 219 sets Carriage Compare Latch 159 which with W2 resets the Carriage Start latch 140 through AND 137, and OR 115.
- 20 35 40 45

When the Increment Counter 150 (FIG. 2r) is decremented to Increment 3 by Motor Advance pulses, a Stop pulse is generated at OR 160 through AND 162 and OR 163 (FIG. 2f). AND's 160a and 160b provide other inputs to OR 160. This turns on the Carriage Register Reset signal at single shot 161, which resets the Increment Counter 150 (FIG. 2r) and the Carriage Command register 78 through OR 85f (FIG. 2f) and provides at Single Shot 160s a Carriage Settling signal. It also turns on the Device End Gate latch 164c through OR 183 (FIG. 2p) causing the Device End latch 164d to turn on through AND 185 and OR 186, producing the Device End signal in the channel status byte. This indicates to the channel that the carriage operation is ended.

- 50 55 60
- 55 60

The Increment 3 signal from the Increment Counter 150 also resets the Low Speed latch 120 (FIG. 2f) through AND 121m (FIG. 2r), gates stop pulses with stop latch 182e or 182c (depending on whether six or eight lines per inch pitch) through an associated stop generator 135, and gates out or inhibits the feedback pulses from the motor emitter heads 104, 106 during stopping.

The Increment Counter 150 advances six increments per line when printing at eight lines per inch and eight increments per line when printing at six lines per inch. The particular one of these two line pitches is determined by which of the six lines per inch or eight lines per inch inputs to AND's 195a-c is energized (FIG. 2r). Accordingly, which of the latches 182e or 182c is set is determined by the condition of these inputs.

- 65 70 75

For a double or triple space, the same Carriage Start latch 140, Increment Counter 150 control and CCB Address Register 56 timing applies for the first line space. But for additional line spaces, Carriage Start latch 140 remains set and the clock 60 is started by the CCB Address Counter Gate trigger 136 (FIG. 2f) which starts the clock 60 for one more cycle. Each clock cycle advances the Increment Counter 150 six or eight increments as explained. When the Space Counter 214 (FIG. 2e) contents is 2, a forced Compare signal rises at AND 218b (FIG. 2e) which resets the Carriage Start latch 140 and brings up the Stop pulse at AND 162 (FIG. 2f) at Increment 3 time, starting the stop sequence, which stops the carriage mechanism. Carriage Register Reset signal from the single shot 161 starts the carriage operation ending sequence as previously described.

Description of a low-speed skip operation is as follows: A Skip Immediate or Skip After Write command will be entered in the Carriage Command Register 78 (FIG. 2*f*) and the bus out bit 0 will turn on the Skip Latch 78*e* in the register 78. The Carriage Start latch 140 (FIG. 2*f*) will be turned on by Immediate Carriage Go or Carriage Go After Print signals from AND 142 or AND 146 through OR 144. The CCB Address Counter Gate trigger 136 is set by the Carriage Start signal through AND 192 and OR 194, and brings up the Carriage Clock Start at AND 180. The Buffer Control latch 80 will be set by the on output of the CCB Address Counter Gate trigger 136 gating the advance of the CCB Address Register 56 at RO time (FIGS. 2*d*-*e*). The clock 60 will advance the CCB Address Register 56 and increment the Increment Counter 150 by a count of six or eight depending on the line pitch selection. The carriage mechanism has been activated by the Carriage Go signal generated by the Carriage Start latch 140 and AND 141 (FIG. 2*f*).

The Carriage Start latch 140 is not reset, so the return of the clock 60 to RO time again sets the CCB Address Counter Gate trigger 136 through AND 192 and OR 194 (FIG. 2*f*) permitting the clock 60 to run an additional cycle. The Increment Counter 150 and the CCB Address Register 56 advance together, and the contents of the addressed bit location in the Carriage Control Buffer 40 is read out to the Carriage Register 83 each clock cycle.

Assume that the skip channel digit stored in the bits 1, 2, 4, and 8 of the Carriage Command Register 78 is stored in byte 5 of the Carriage Control Buffer 40, and assume also that the forms were located at line 1 when the carriage skip was started. As shown in the timing diagram of FIG. 7, a Carriage Register Compare signal will occur at AND 77*c* (FIG. 2*f*) when the contents of CCB position 5 is read into the CCB register 83. Inverter 77*d* provides a Not Carriage Register Compare signal. This will set the Carriage Compare latch 159 through AND 113 and OR 117 (FIG. 2*f*). AND 113*b* provides another input to OR 117. Further advance of the CCB Address Register 56 is inhibited after RO time of the current clock cycle because CCB Address Counter Gate trigger 136 is reset through AND 67 and OR 95. The CCB Address Register 56 will have advanced four times. Carriage Compare signal from the latch 159 resets CCB Address Counter Gate trigger 136 and the Carriage Start latch 140. The Increment Counter 150 (FIG. 2*r*) is advanced by the R3 time, W1 time clock pulses so that its contents are changed to a count of 32 or 24 depending on whether a line pitch of 6 or 8 is called for. The clock 60 (FIG. 2*i*) completes the present cycle and stops in RO time. The Carriage Go signal from the Carriage Start latch 140 (FIG. 2*f*) started the carriage by setting the Low Speed latch 120 to produce an Initial Advance signal at OR 100. Carriage Compare latch 159 is reset by AND 117*a*.

The carriage emitter signals from OR 100 (FIG. 2*r*) subtract from the Increment Counter 150 (FIG. 2*r*) causing it to decrement one for each feedback pulse. When the Increment Counter 150 contents reaches 3, the Increment 3 signal brings up the Stop pulse at AND 162 (FIG. 2*f*). Carriage Register Reset signal from OR 160 and single shot 161 (FIG. 2*f*) resets the Command Register 78 (FIG. 2*f*) and the Increment Counter 150 (FIG. 2*r*), and initiates the carriage stopping sequence by resetting the Low Speed latch 120 (FIG. 2*r*) through AND 121*m* (FIG. 2*r*). Reset of the Low Speed latch 120 (FIG. 2*r*) causes the mechanism to stop as previously described. The carriage has advanced four lines from 1 to 5. Carriage Control Buffer 40 (FIG. 2*h*) has advanced from position 2 to position 6.

Assume that the command is loaded to skip to a forms channel 15 line spaces or more from the present print line. Specifically assume that the channel digit is stored in position 20 of the Carriage Control Buffer 40 and line 1 was the last line printed. In this case, the clock 60 advances the Increment Counter 150 a count of 8 or 6 increments for each clock 60 cycle advance as the clock scans the line positions in the buffer 40 until the Increment Counter 150 reaches a count of

152 or 114. For each of the clock pulses the CCB Address Register 56 is advanced until a Carriage Register Compare signal occurs at AND 77*c*, (FIG. 2*f*) at CCB Address 20, turning on Carriage Compare latch 159 at W0 time through AND 113 and OR 117 (FIG. 2*f*). Further advance of the CCB Address Register 56 is inhibited when Buffer Control signal from Buffer Control latch 80 is gated down after reset of CCB Address Counter Gate trigger 136 at W1 time, after compare by RO time through AND 196. Since the Buffer Control signal is a DC level signal applied to the DC gates 56*b* and 56*c* of CCB 1 trigger 56-1, RO time which is a pulse signal applied to the AC inputs 56*d* and 56*e* of trigger 56-1, will also advance the CCB Address Register 56 to 21 even though RO time resets Buffer Control latch 80. The Increment Counter 150 is decremented to zero by the successive Motor Advance feedback pulses, and carriage advance continues. When Increment Count 3 rises, it turns off the low speed latch 120 and generates the Stop pulse at AND 162 (FIG. 2*f*). The same stopping procedure will occur as described previously and the form will stop in position 20 with the CCB Address Register 56 containing address 21.

When the Increment Counter 150 (FIG. 2*r*) initially advances through counts 32 and 84, Medium and High Speed conditions were generated through AND's 121*i* and 121*k* which set the Medium Speed latch 122 and the High Speed latch 124 (FIG. 2*r*). The Upshift latch 126*b* is set through AND 110*e* and OR 125, and gates the set of the Medium Speed latch 122 in AND 121*i* at increment 32. When the Increment Counter 150 reaches a count of 84, the High Speed latch 124 is turned on at AND 121*k* under the control of the Upshift latch 126. Thus, for a few microseconds, carriage advance occurred in Low Speed and was then changed to a Medium Speed and finally a High Speed mode by operation of these latches 122 and 124. Of course, no carriage motion actually occurred during this short time. The High and Medium Speed modes are removed a number of increments, for example, at increment counts of 72 and 24, respectively, before the stopping point by the reset of the High and Medium Speed latches 124 and 122 through AND's 121*l* and 121*j* and OR's 122*b* and 122*a*. Thus it will be seen that a high-speed skip will occur if the channel skip is to a location 84 increments away. The specific skip range depends on the carriage drive velocity time characteristic. Likewise, control of the deceleration by decode of the displacement in line increments to the stopping point, using the Line Counter contents, can be used in other types of carriage mechanisms.

During a space or skip operation, the printer may come to the end of a form. When the printer is at the next to last line of a form, but the carriage emitter pulse indicating that the forms are moving to the last line has not occurred, the Carriage Address Register 56 contains the address of the last line of the form and the Carriage Control Buffer Register 83 will contain the byte associated with the next to last line of the form. When the Increment >3 pulse is received for the last line of the form, the Carriage Control Buffer Register 83 will be loaded with a byte containing the flag bit indicating the end of the document. Detection of the flag bit resets the CCB Address Register 56 through AND 175 and OR 174. This is a DC reset and occurs at RO time, overriding the CCB Address Register 56 advance which normally occurs at RO time. When the clock 60 stops at RO time, the CCB Address is 1, the Carriage Control Buffer Register 83 contains a flag bit and the form is at the last line and is moving. ANDs 56*a*, 57*b* decode Address 0 for providing a CCB Address 0 or flag at OR 58, and CCB Address 1, respectively.

A Carriage Runaway latch 200 (FIG. 2*d*) is provided which is set through AND 202, reset through OR 201 by Carriage Go or by an input from OR 172 from OR 171, and provides a Runaway signal at AND 203 (FIG. 2*e*) if CCB Address 1 occurs with the Carriage Runaway latch 200 set (Invertor 205 provides a Not Carriage Runaway signal). This senses that two channel ones occurred during the same forms command so that a complete form has passed by the print line without

stopping the mechanism. The parity check circuit 89 is checked for parity every WO time on an ODD bit basis through AND 204 and OR 204a (FIG. 2f). Normally, a carriage emitter signal should occur for every line space although the emitter pulse which occurs during stopping is not functionally necessary. The Carriage Command Register 78 may have been inadvertently loaded with a forms channel digit which was not in fact loaded into the carriage control buffer 40. This is a programming error. When the carriage is set in motion, a search will be made for this valid channel in the buffer 40 but none will be found. If a complete form passes by the print line as sensed by the existence of two carriage address 1 conditions in the same command, a channel code did not exist and a Carriage Runaway condition is occurring.

When operating in an Increment Command mode and an Increment Command is received over Bus Out 69, such as Bus Out 0, 1, 2, 3, 4, Not 5, 6 and 7, for example, with Gate Command Register signal from AND 65B (FIG. 2b) the Increment Command latch 1164 (FIG. 2r) is set through AND 116 (FIG. 2q) and the increment data is gated from the Bus Out into the Increment Counter 150 to set it to a specific increment count. An Increment Carriage Go signal is developed at single shot 182 which through OR 209 selectively gates through AND's 121a-n (FIG. 2r) a particular arrangement of the Low, Medium and High Speed latches 120, 122 and 124 (FIG. 2f). For example, if the command was to increment 5 increments, the 1 and 4 counter stages would be set, the Low Speed latch 120 would be set through AND 120n, and stop latch 182b would be set for later controlling its stop generator 135c. Low Speed signal from latch 120 produces an initial advance pulse through single shot 102, and additional feedback pulses are produced by pickup 104 from emitter 111 to drive the Motor Drive triggers 96A, 96B through OR 100.

The Increment Counter 150 (FIG. 2r) decrements or has a count of 1 subtracted for each motor advance pulse from OR 100, and when it reaches a count of 3, a series of three stop pulses are generated by Stop Generator 135c which is associated with and activated by AND 205b. The increment Count 3 signal generates a reset signal at single shot 161 (FIG. 2f) which resets the carriage control register 78 (FIG. 2f), the Increment Counter 150 and the Device End Gate latch 164c (FIG. 2p). The Low Speed latch 120 is reset by Increment Count through AND 121m (FIG. 2r).

Should the Increment Command be > 43, the Medium Speed latch 122 (FIG. 2f) will be set through AND 121i (FIG. 2r) in conjunction with the on output of the Upshift Latch 126b. When the Increment Counter 150 is reduced to a count of 24, the Medium Speed latch 122 is reset through AND 121j, and the carriage motor 22 (FIG. 1) continues to operate under control of the Low Speed latch 120 which is also turned on. Should the Increment Command be > 84, the High Speed latch 124 will be set through AND 121k under the control of the Upshift latch 126b which is turned on through OR 125 (FIG. 2r) and the carriage motor 22 will start at Low Speed, shift sequentially to Medium and then High Speed. When the Increment Counter count is reduced to 72 by Motor Advance pulses, the High Speed latch 124 is reset through AND 121l between motor advance pulses. The Downshift latch 126a is set to inhibit Motor Advance pulses at AND 110g by turning the High Speed latch 124 off, and is reset to restore the drive by the Medium Speed latch 122 and Medium Speed Emitter signals through AND 220b, OR 221 and inverter 222. AND 220a provides for reset of the Downshift latch 126a by the Medium Speed latch 122. Likewise, when the Medium Speed latch 122 is reset by Increment count 24, drive is momentarily inhibited at AND 220e by the Downshift latch 126a.

For increment commands of 3, 2, or 1, the Stop Generators 135A, 134, 133 (FIG. 2s) are selectively set by AND's 121c, b or a during the Increment Go signal from single shot 182 (FIG. 2r). For increment commands of 4-8, a particular one of the latches 182a-e will be set during the Increment Go signal, and when the Increment Counter 150 decrements to 3, a particu-

lar one of the associated Stop Generators 135B-F will be gated by its respective AND 205 a-e to provide a specifically timed set of stopping pulses through OR 223 and OR 100 (FIG. 2s), the single shots 135 a, c and e having, respectively, for example, time intervals on the order of 1.5, 1.6, and 1.8 ms. on an average, approaching 2 ms. for 8 increments, and approaching 1 ms. for 3 increments.

From the above description and the accompanying drawings, it will be apparent that the present invention eliminates the requirement for the operator to prepare and install a paper control tape. Troubles caused by wear and tear of paper control tapes are thereby eliminated. The maintenance problems connected with the paper tape sensing brushes are also eliminated. A tapeless carriage control system embodying the features of the present invention is program compatible with existing control systems. Programs may be readily changed by simply loading a new one into the carriage control buffer 40.

While the invention has been particularly shown and described with reference to a preferred embodiment thereof, it will be understood by those skilled in the art that various changes in form and details may be made therein without departing from the spirit and scope of the invention.

What is claimed is:

1. In a control system for a printer carriage having drive means operated by pulses from a pulse circuit to actuate the carriage a predetermined number of increments each of which is only a small fraction of a single line space for a document on which a printing operation is to be performed and thereby control both the line pitch and the number of lines said document is advanced,

an increment counter comprising a direct settling decrementing multistage counter having a plurality of different increment outputs, control means connecting said increment counter to a Command Bus for direct settling said increment counter a predetermined number of fractional line space increments in accordance with a Bus Out command to determine the line pitch and the number of lines said document is to be advanced,

emitter means driven with said carriage by said drive means to produce a pulse for each fractional line space increment advance and connected to said pulse circuit and to said increment counter to activate said pulse circuit and decrement said increment counter a count of one for each increment advance of said drive means, and means including speed control means connected to said pulse circuit and to said increment counter operable to provide a first pulse for starting said drive means at one speed and further operable to change the speed of the drive means to a higher value at a predetermined increment count regardless of the number of increments advanced for each line space.

2. The invention as defined in claim 1 characterized by said speed control means including a plurality of bistable control devices connected to said increment counter and to said pulse circuit for selectively changing the speed of operation of the pulse circuit in different directions at different predetermined increment values respectively, which are the same for a change in one direction regardless of the number of increments advanced.

3. The invention as defined in claim 2 characterized by said means including said speed control means connected to said increment counter and to said pulse circuit comprising a plurality of different gate circuits selectively connecting different ones of said increment outputs of said increment counter to different ones of said bistable control devices to provide a plurality of different increment value outputs which effect selective operation of said speed control means bistable devices to increase and decrease the speed of said drive means at predetermined increment counts in sequence.
